Primary Examiner — Jack Reickel*Assistant Examiner* — John M Otte(74) *Attorney, Agent, or Firm* — Hauptman Ham, LLP(57) **CLAIM**

The ornamental design for a display screen with an animated graphical user interface, as shown and described.

DESCRIPTION

FIG. 1 is a first image of a front view of an animated display screen with graphical user interface showing a first embodiment of our new design;

FIG. 2 is a second image thereof;

FIG. 3 is a third image thereof;

FIG. 4 is a forth image thereof;

FIG. 5 is a first image of a front view of an animated display screen with graphical user interface showing a second embodiment of our new design;

FIG. 6 is a second image thereof;

FIG. 7 is a third image thereof; and,

FIG. 8 is a forth image thereof.

The dot-dash broken lines showing of a display screen in all views form no part of the claimed design. The dashed broken lines showing of the graphic elements form no part of the claimed design.
